MOTORCYCLE ROCKER ARM COVER

Jefferson R. Smith, Torrance, Calif.
(1872 W. 166th St., Gardena, Calif. 90247)

Filed June 3, 1969, Ser. No. 17,499

Term of patent 14 years

Int. Cl. D15—01

U.S. Cl. D77—1

FIG. 1 is a top plan view of a motorcycle rocker arm cover embodying my new design.

FIG. 2 is an end elevational view as seen from the upper margin of FIG. 1.

FIG. 3 is an end elevational view as seen from the other end thereof.

FIG. 4 is an elevational view as seen from the left of FIG. 1.

FIG. 5 is an elevational view as seen from the right of FIG. 1.

I claim:

The ornamental design for a motorcycle rocker arm cover, substantially as shown.
